UNITED STATES PATENT OFFICE

GEORGE E. MARLATT, OF PASADENA, CALIFORNIA

TYPOGRAPHICAL ASSEMBLING AND DISTRIBUTING MACHINE

Application filed July 5, 1928. Serial No. 290,430.

My invention relates to typographical machines of the kind in which circulating matrices are released from a magazine and assembled in line and then presented to a mold in which the printing type is cast against the line of matrices, the matrices subsequently being distributed to their individual channels in the magazine from which they were released.

10 Certain features clearly indicated by similar reference characters will be found in common in this disclosure and in my Patent No. 1,679,318. Particularly, it relates to improved means for conducting the matrices 15 into the magazine channels, with the object in view of rendering this operation more positive than heretofore and also simplifying the machine and increasing the capacity of the magazine without increasing its size. 20 Heretofore the magazines of linotype machines have been made about one-third wider at their receiving end than the accumulative thickness of the stored matrices would actually require. The necessity for the excess width of the magazines at their receiving end has been due to the fact that the matrices in dropping from the distributing bar could not clear the lower distributor screw; therefore entrance partitions were 25 provided equal in number to the magazine channels, the resultant channels between such partitions being of sufficient dimensions to receive the matrices following their interference with the lower distributor screw. It 30 is the width of these partitioned entrance channels that has determined the width of the magazine at the receiving end, and this present invention provides for eliminating the entrance partitions and substituting therefor opposed-groove channels similar to those in the magazine and in continuation thereof. With such construction the magazines may be rectangular in shape instead of the usual trapezoidal form, and the channels 35 therein may be parallel, thus greatly reducing the manufacturing cost of the magazine. Also, the matrices will more readily enter, travel through, and escape from the parallel channels than in the case of converging 40 channels; the matrices will be distributed

quicker by reason of the reduced width of the magazine at its receiving end, and additional channels may be added to the magazine without increasing its weight. Paralleling the channels of the magazine also renders feasible the form of matrix escapement of this disclosure, and, as explained in my application for patent before mentioned, this escapement in turn renders possible the simplification of the keyboard mechanism. An example of the partitioned entrance above referred to as eliminated may be found in the patent to O. Mergenthaler, No. 436,532. A further principal object in view is to provide for selectively distributing two sets of matrices to a single magazine and releasing them therefrom, together with an interconnection whereby the distributing and releasing means are shifted in time with each other according to the set of matrices selected for use.

In the accompanying drawings:

Fig. 1 shows the usual trapeziform magazine overlying the rectangular form of magazine shown in connection with the principal figures of the drawings, and illustrates how the magazine may be widened at its lower end and narrowed at the receiving end in order to provide for additional channels without increasing its total area and weight.

Fig. 2 shows the usual trapeziform magazine between a rectangular magazine of less size but with an equal number of channels, and a rectangular magazine as wide as the trapeziform magazine at the receiving end but capable of containing more channels than the usual trapeziform magazine.

Fig. 3 is a vertical longitudinal view, partly in section, of the distributor, magazine, and assembler-delivery throat of a linotype machine in which the matrices are delivered in vertical position to the magazine-entrance grooves and therefore necessitating a curved entrance channel. This view shows the application of my distributor improvements to a machine or that portion thereof thus constructed, together with shift mechanism interconnecting the distributor improvements and the escapement operating reeds.

Fig. 4 is a fragmentary section on the approximate line 4—4 of Fig. 3.

Fig. 5 is a vertical section through part of a linotype machine, showing the application of my distributor improvements to a linotype machine in which the matrices are delivered in a non-vertical position to distributing points and the usual curved entrance channel is eliminated.

Fig. 6 is a section on the approximate line 6—6 of Fig. 3.

Fig. 7 is a sectional plan view taken on the line 7—7 of Fig. 3.

Referring to Figs. 3 and 4, the matrices X are in usual manner conveyed by means of the distributor screws 1, 2 and 3 along the distributor bar 4 until they reach a point above their individual channels. The omission of a combination of ribs 5 on the bar 4 above any entrance channel indicates the retention of a corresponding combination of teeth on the matrices destined for such channel; therefore the matrices are released from the bar when their retained combinations clear the ends of a combination of ribs thereon. As commonly constructed, the matrices have their screw-engaging lugs flush with their forward or lead side as they appear when traveling on the bar 4, and their distributing teeth flush with the opposite side, and since matrices of one font may exceed in thickness those of another font, I terminate the distributing combinations on the bar 4 with reference to matrices of the thickest font; therefore matrices of thinner fonts will not immediately enter their channels when released from the bar 4, but will be supported by means of their upper lugs on rails 7 and 8 until they reach opposed grooves 7^a and 8^a formed on facing sides thereof, as more fully explained in my co-pending application Serial No. 546,383 (now Patent No. 1,679,317). With reference to the rails 7 and 8, this present invention is concerned principally with the angles of the grooves 7^a and 8^a relative to each other and relative to the matrices while suspended from the distributor bar. It will be noted that the outer grooves 8^a and 8^b are continuous with similar grooves 9^a in the magazine entrance 9 and that these grooves 9^a are in continuation of the grooves 10^a in the magazine 10; but the inner grooves 7^a are of necessity interrupted by the lower distributor screw 3. The angle of the outer grooves 8^a relative to the suspended matrices is such that the lower, outer lug X¹ of the matrices will clear the ribs separating the grooves 8^a while the matrices are being conveyed on the distributor bar 4. When the matrices reach their individual channels their lower inner lugs X² immediately enter the inner grooves 9^a and both upper lugs X³, X⁴ enter the grooves 7^a, 8^a. The inner grooves 7^a are parallel with the opposite grooves 8^a but are of receding depth to avoid

interference with the horizontal travel of the matrices; hence both upper lugs on the matrices will remain in their channels except as the inner channel is interrupted by the lower distributor screw. A short distance below the lower distributor screw the grooves 9^a in the magazine entrance channel approach each other, as at 9^b, therefore before the inner upper matrix lug X³ leaves its groove 7^a both lower matrix lugs will be fully engaged in their channel 9^a and the lower distributor screw will prevent the upper outer lug X⁴ from leaving its channel. In order that the upper lug X³ of the matrices may not enter the groove of the lower screw, the groove is made steeper than usual so that its vertical measurement is less than that of the matrix lug X³ and will be bridged by the lug when passing the lower screw. (See Fig. 4.) This additional steepness of the groove in the lower screw results from making the lower screw of less diameter than the upper screws. In addition I prefer to make the thread in the lower screw shallower than usual, especially when employed as in Fig. 5, in order to insure against interference between the body of the matrix and the screw thread. When employed as in Fig. 3, the shallow thread renders it possible to make the grooves 7^a, 8^a correspondingly less steep. It will be apparent that the channel angles as described and illustrated are such that only one matrix lug at a time may remain out of engagement with its groove, and the simultaneous engagement of three lugs with their grooves will retain the matrix in such position that the disengaged lug will enter or re-enter its groove at the appropriate time. This arrangement makes possible the elimination of the usual magazine entrance partitions and a consequent reduction in the width of the magazine as stated in the beginning of this specification and in the description of Figs. 1 and 2 of the drawings. Only a sufficient number of the usual magazine entrance partitions 9^c are retained to space apart the inner and outer channel plates of the magazine entrance 9 and these may be in a plane in continuation of the magazine partitions. The outer grooved rail 8 is secured to a pair of brackets 11 movable with a shaft 12 mounted on the distributor beam 13 in order that the rail 8 may be moved outwardly and upwardly to provide access to the matrices or other parts. The foregoing description of Fig. 3 also applies to Fig. 5 so far as similar reference numerals with different exponents are employed to designate corresponding parts. But it will be noted that in Fig. 5 no magazine entrance channel is employed, and its elimination is made possible by the improvements above described in connection with the rails 7 and 8. The disclosures of Figs. 3 and 5 may be combined in the same multiple-magazine machine as in the

case of my application Serial No. 139,719, filed Oct. 5, 1926 (now Patent No. 1,681,672). In Fig. 5 the distributor bar 4^a is shown at a steeper angle than the magazine 10 in order that the initial drop of the matrices may be fast enough to cause them to enter the magazine in time to avoid interfering with a following matrix. This angle of the distributor bar may be more or less according to requirements.

In order to insure that the inner matrix lugs will readily enter the inner channel grooves 9^a, I prefer to flare the entrances to these grooves, as shown in Fig. 4, the flared portion being formed in a bar 7^e; similarly, as shown in Fig. 6, the outer grooves 8^a are flared near their lower ends in order that the outer lower matrix lugs X¹ may readily enter therein. As further insurance that the matrix lugs X³ will enter the flared entrances to the channels 9^a, the grooves 7^a in the inner channel rail 7 may be choked toward their lower ends as illustrated in Fig. 4. For manufacturing convenience, the outer rail 8 is constructed in two parts, the lower part having the flared portion 8^e of the channels, while in the upper part the channels may be straight, all as illustrated in the drawings, the two parts being secured to the brackets 11 as before described.

The foregoing description explains my magazine entrance channel improvements as used in connection with magazines containing a single font of matrices. In order that the same improvements may be employed for delivering matrices to a magazine containing two fonts of matrices, I provide as follows: The channel grooves 9^a in the magazine entrance 9 and also the grooves 10^a in the magazine 10 are provided in pairs, each one of a pair of magazine channels containing matrices of similar value or character but of different size or design, so that two fonts of matrices are arranged in the magazine, alternating character by character in alternate channels. Referring to Figs. 4 and 6, it will be noted that a single opposed-groove channel in the rails 7 and 8 and bar 7^e serves for each pair of grooved channels in the magazine entrance 9. Alternate grooves 9^a in the entrance channel are flared at their entrance, as at 9^e. In Fig. 6 the entrance rails 7 and 8 and bar 7^e are shown as adjusted to deliver matrices to the flared channels 9^a, and in Fig. 4 the rails and bar are adjusted to register with the alternate set of channels 9^a. In order that the rails and bar may be thus adjusted longitudinally, the inner rail 7 and bar 7^e are secured to a pair of brackets 20 mounted to slide on the distributor rail 4, and the shaft 12 which supports the outer rail 8 slides in a pair of rigid brackets 21. The hub portion of the brackets 11 which support the outer rail is provided with a groove 11^e which is engaged by a tongue 20^e

on each bracket 20; movement of the inner brackets 20 on the distributor rail 4 will therefore cause the outer brackets 11 to move therewith and the channeled rails will accordingly move together for registration with a selected set of channels 9^a in the magazine entrance. Since the distance between different matrix channels varies according to the varying thickness of matrices according to character, and the movement of the rails 7 and 8 and bar 7^e must be limited to the distance between two closely adjoining channels, it therefore is necessary to flare alternate magazine entrance grooves 9^a varying amounts according to the distance therebetween. It will be apparent from a comparison of Figs. 4 and 6 that a movement of the rails and bar a distance equal to the distance between the narrowest pair of channels, will serve for delivering matrices to all wider pairs of channels regardless of their varying measurements. The rails 7 and 8 and bar 7^e are shiftable to the left from the position they occupy in Fig. 4 as determined by the stop 4^a, and since the stop 4^a at the left of Fig. 4 appears at the right of Fig. 6, the rails and bar are shiftable to the left from their position in Fig. 6 back to the position they occupy in Fig. 4.

As explained in my Patent No. 1,679,318 before mentioned, the magazines for holding two sets of matrices are provided with two sets of escapements 27, one set having its contact point 27^a in a rear position and the other set thereof having the similar point in a forward position, in order that the keyboard-controlled actuating reeds 17^b may be adjusted from one set to the other according to the set of matrices selected for use. In the present case I provide for simultaneously shifting both the distributing and releasing devices in a manner convenient for the operator when seated at the keyboard. With this purpose in view, an operating shaft 22 is mounted at its upper end in the distributor beam 13, and at its lower and forward end in a bracket 23 extending from the usual assembler entrance throat 16. The shaft 22 has secured thereto an arm 24 having a groove 24^a which engages one of the brackets 20 before described as movably supporting the rear channel entrance rail 7 and bar 7^e; hence, when the shaft 22 is rocked in manner to be described, the channel entrance elements will be shifted in a selected direction. Movement of the brackets 20 and other parts is limited by stops 4^a (Fig. 6). At its forward end the shaft 22 is provided with a crank arm 25 directly controlled by a link 26 guided in an opening 16^a through the throat 16. An intermediate link 28 connects the link 26 with an operating handle 29 secured to a shaft 31 mounted at the rear of the assembler throat. The frame 42-44 which supports the escapement actuating reeds 17^b

is connected to the operating handle 29 by means of a link 30. It will be apparent that through the connections as described, the channel entrance elements and escapement-
5 actuating reeds will move in unison with movement of the handle 29 in a selected direction as determined by the set of matrices selected for use.

Having described my invention, its construction and mode of operation, what I claim as new and desire to secure by Letters Patent of the United States, is:

1. In a typographical machine, in combination, matrices having lugs on each end of opposite edges thereof, a distributor bar on which said matrices are conveyed for release to individual opposed-groove channels, upper and lower distributor screws for conveying said matrices to their points of release from said distributor bar, and means for permitting the lugs on said matrices to engage the grooves of said channels and guide said matrices therethrough regardless of the fact that the continuity of said channels is broken by one of said distributor screws, said means consisting in so shaping the grooves of said channels that only one of the lugs on said matrices will be out of engagement with said grooves at one and the same time after said matrices have been disengaged from said distributor bar and distributor screws and while passing through their channels.

2. A combination as specified in claim 1, characterized by the fact that the matrices therein recited may be released from said distributor bar in advance of their channels and be supported independently of said bar while being conveyed to their channels.

3. In a typographical machine, in combination with a distributor bar and matrices suspended therefrom for release to their individual channels, opposed-groove channels to receive said matrices when so released, lugs on each end of each edge of said matrices for engaging the grooves of said channels, a distributor screw for engaging the lower inner lug on one edge of said matrices, and means for tilting said matrices in order that the upper inner lug thereon will pass said distributor screw when the matrices are released from said distributor bar, said means comprising an inner groove interrupted by said distributor screw and having its portion above said distributor screw decreasing in depth from a point outside the upper lugs of said matrices to a point beneath said lugs and adjacent said distributor screw, the portion of said groove below said screw being of uniform depth and substantially parallel to a line extended through the center of said distributor bar and said matrices when suspended therefrom, and a continuous outer groove opposite said upper portion of said interrupted channel and said distributor screw, said continuous groove extending angularly relative to said

center line of said distributor bar from a point beneath the upper outer lugs on said matrices to a point beyond and below the lower outer lugs thereon and being then deflected toward said center line and therebey 70 continuing equally spaced away from the lower portion of said interrupted channel, whereby said lower inner lugs on said matrices become a pivotal point about which said matrices are tilted while their inner upper lugs are guided in the upper portion of said interrupted grooves and their outer upper lugs are guided in said outer grooves, the lower outer lugs engaging said outer channel at that part thereof where it is deflected towards said center line, and said deflected part serving to force the upper inner lugs of the matrices into said inner groove after they have passed said distributor screw.

4. A combination and structure as set forth in claim 3 characterized by the fact that the center line of the distributor bar therein recited is disposed at an angle between perpendicular and horizontal, that the inner and outer upper lugs on the matrices are guided for propulsion by inner and outer upper distributor screws parallelling said distributor bar and that the thread of the distributor screw which engages the lower inner lug of the matrices is of less depth than the threads of said upper distributor screws in order that said distributor screw will present a minimum of interference with the inner upper lugs of said matrices when passing said screw.

5. A combination and structure as set forth in claim 3 characterized by the fact that the portion of the outer grooves therein recited as being disposed at an angle to the center line of the distributor bar are formed in a plate mounted for upward and outward movement in order to provide access to the remaining portions of the opposed-groove channels.

6. In a typographical machine, in combination, matrices having upper and lower lugs on opposite edges thereof, two upper screws for engaging the upper lugs of said matrices and conveying them to points of distribution, a lower similar screw for engaging a lower lug of said matrices, opposed-groove channels for receiving the lugs of said matrices at their points of distribution, and means for providing a three-lug guidance for said matrices while passing said lower screw, guided in said channels, said means consisting of deflecting one of the grooves of said channels from its upper end to a point beyond and out of interference with a lower matrix lug and below said lower distributor screw without interrupting its continuity, and similarly deflecting the opposed groove of said channels from its upper end to a point where it is interrupted by said lower screw, whereby said matrices will be deflected to cause an upper lug thereof to pass said lower screw, a

continuation of the interrupted groove occurring immediately beneath one lower lug of the matrices and the uninterrupted groove being shaped to engage the other lower lug of the matrix before the opposite but upper lug reaches the interruption in its channel, while the other upper lug remains in continuous engagement with the uninterrupted channel, due to its spacing from the interrupted channel.

7. In a typographical machine, in combination with matrices having upper and lower lugs on opposite edges thereof, a distributor bar from which said matrices are suspended for release at their individual destinations, a pair of parallel and opposite screws for engaging the correspondingly opposite upper lugs of said matrices and conveying them to their individual destinations, and a third screw for engaging a lower lug of said matrices in co-operation with said pair of screws; a series of opposed-groove channels for receiving the lugs of said matrices when released from said distributor rail, one of the grooves of each of said channels being interrupted by said third distributor screw and the portion thereof lying above said screw receding in depth towards said screw in order to cause an upper lug of said matrices to clear said screw, the opposite groove of each of said channels being continuous but receding in position to a point below said third distributor screw in order to clear a lower lug of said matrices prior to their release from said distributor rail, said channel approaching said interrupted channel at a point below said third screw and continuing uniformly spaced therefrom to the end of said channels.

8. In a typographical machine, in combination, matrices having upper and lower lugs on opposite edges thereof, a distributor bar from which said matrices are suspended for release at their individual destinations thereon, a pair of parallel and opposite conveyer screws for engaging the corresponding upper lugs of said matrices and conveying them to their individual destinations, a third screw co-operating therewith and engaging one of the lower lugs on said matrices, opposed grooves terminating adjacent the individual points of release of said matrices and in position to receive the upper lugs thereof, one of said grooves receding in depth between the upper lug of said matrices and said third distributor screw in order to guide said upper lug clear of the thread of said third screw, and the opposite groove receding in position between the upper lug of said matrix and a point beyond and below the lower lug thereof in order that it will not interfere with the travel of said matrices to their points of release under control of said distributor screws and will serve to guide the upper lug of said matrix while passing said third distributor screw following the release of the matrix

from the distributor bar, said lower distributor screw serving to force said matrix into said opposite groove.

9. In a typographical machine, a distributor bar, a matrix suspended therefrom for travel thereon but capable of being released therefrom, opposite upper and lower lugs on said matrix, a set of conveyor screws comprising two upper screws for engaging the upper lugs on said matrix and a lower screw for 70 engaging one of the lower lugs on said matrix, and opposed grooves for engaging the lugs on said matrix when it is released from suspension on said distributor bar, said grooves being deflected relative to said matrix when suspended from said distributor bar in order that a lower lug on said matrix will pass the partitions of said grooves while being conveyed on said distributor bar 75

80. 10. In a typographical machine, in combination with a distributor bar for matrices and an oblong matrix having lugs on each end of its longer edges, a single upper conveyor screw for engaging the upper lug on one edge of said matrix, a second screw for similarly engaging the upper lug on the opposite edge of said matrix, a third screw for engaging the lower lug on said opposite edge, a grooved rail between said second and third screws, the grooves in said rail receding in 85 depth from said second to said third screw and towards said matrix when in front of said grooved rail, and a second grooved rail 90 opposite said rail with the receding grooves and said third conveyer screw, the grooves 95 in said second rail being of uniform depth but receding from said matrix to clear the lower lug thereon when said matrix is between said grooved rails.

11. In a typographical machine, in combination, a distributor bar for matrices, matrices having lugs on opposite ends of each edge thereof, an upper distributor screw for engaging the upper lug on one edge of said matrices, an upper and a lower distributor screw for engaging, respectively, the upper and lower lugs on the other edge of said matrices, and opposed-groove channels for receiving and engaging the lugs of said matrices and conducting them from said distributor bar, one groove of each of said channels being interrupted by said lower distributor screw and the opposite groove being continuous, the upper end of the upper section of said interrupted groove registering in 100 depth with the groove in said upper distributor screw for receiving an upper lug of said matrices from said screw, and the lower end of said channel section clearing the lower distributor screw for the purpose of deflecting 105 said upper lug to pass said lower screw, the lower section of said interrupted channel registering in depth with the groove in said lower screw for receiving a lower lug of said matrices, the upper portion of said continuous 110

- channel being parallel with the line of the upper section of said interrupted channel extended to a point beyond said lower distributor screw, and the lower portion thereof being deflected toward the lower section of said interrupted channel, in order that not more than one lug on said matrices will be out of engagement with said opposed-groove channels at the same time.
12. In a typographical machine, opposed-groove channels for conducting matrices from a distributor bar, one channel of each of said grooves being continuous and the opposite channel being interrupted by a distributor screw, and means for permitting an upper channel-engaging lug on said matrices to pass said distributor screw without dislodging said matrices from their channels, said means consisting in offsetting said interrupted channel an amount equal to its depth and at a point between its upper and lower sections, and similarly offsetting said continuous channel at a point below the offset in said interrupted channel.
13. A structure as set forth in claim 12 characterized by the fact that the portion of the opposed-groove channels beyond the offsetting in said channels constitutes the magazine in which the matrices are stored.
14. A structure as set forth in claim 12 characterized by the fact that the portion of the opposed-groove channels below and beyond the offsetting in said channels constitutes a magazine-entrance element through which the matrices are conducted to a storage magazine.
15. A structure as set forth in claim 12 characterized by the fact that the portion of the continuous channels therein recited as being above the offset in said channels, is mounted for upward and outward movement in order to provide access to the matrices and structure normally concealed thereby.
16. In a typographical machine, in combination, a distributor for matrices, an assembler delivery throat, a channeled magazine through which matrices pass from the distributor to the assembler delivery throat, two sets of channels therein adapting said magazine to accommodate two sets of matrices, a distributor bar having a single set of matrix releasing combinations, a single set of escapement-actuating reeds adjustable to release matrices of a selected font from the magazine, a series of channels between said magazine and said distributor bar equal in number to the matrix-releasing combinations on said distributor bar and adjustable to deliver matrices to a selected set of channels in said magazine, and an interconnection between said adjustable series of channels and said adjustable escapement-actuating reeds for causing said channels and said reeds to move in unison relative to the font of matrices selected for use.
17. In a typographical machine, in combination, a channeled magazine for matrices, a distributor bar for releasing matrices destined to said magazine, a series of opposed groove channels for conducting the matrices from the distributor bar, a lower distributor screw interrupting said series of opposed-groove channels, and a midway flare in the grooves of said series of channels for insuring the engagement of the matrices with said grooves while passing said lower distributor screw.
18. A combination as set forth in claim 17 characterized by the fact that the series of opposed-groove channels therein recited are adjustable relative to a selected series of unequally spaced pairs of opposed-groove channels for accommodating two sets of matrices, and including a flare at the mouth of one channel in each pair thereof in order that the matrices will enter therein, regardless of the unequal spacing thereof and regardless of the adjustment selected for said first mentioned series of opposed-groove channels.
19. In a typographical machine, in combination with a distributor bar, a set of distributor screws for conveying matrices thereon to points of release into opposed-groove channels, and matrices having lugs thereon for engaging the grooves of said channels, a series of magazine channels provided in pairs for accommodating two fonts of matrices, a series of channels between said distributor bar and said magazine channels provided singly, a set of escapements for each font of matrices, a set of actuating reeds shiftable from one to the other of said sets of escapements, and interconnecting means whereby said intermediate series of channels and said actuating reeds may be shifted in unison according to the set of matrices selected for use.
- Signed at Pasadena, Los Angeles County, California, this 29th day of June, 1928.
